UNITED STATES PATENT OFFICE.

WILLIAM J. GEORGE, OF JOHNSTOWN, PENNSYLVANIA.

WASHING-MACHINE.

SPECIFICATION forming part of Letters Patent No. 657,063, dated August 28, 1900.

Application filed January 26, 1900. Serial No. 2,893. (No model.)

To all whom it may concern:

Be it known that I, WILLIAM J. GEORGE, a citizen of the United States, residing at Johnstown, in the county of Cambria and State of Pennsylvania, have invented a new and useful Washing-Machine, of which the following is a specification.

The invention relates to improvements in washing-machines.

10 One object of the present invention is to improve the construction of washing-machines and to provide a simple and comparatively-inexpensive one designed for domestic and laundry use and adapted for rapidly and 15 thoroughly washing clothes at the expenditure of a minimum amount of labor without wearing, tearing, or otherwise injuring the fabrics.

20 A further object of the invention is to provide a washing-machine of this character adapted to force air and steam through the clothes and capable of effectively rinsing the same to complete the washing operation.

25 The invention consists in the construction and novel combination and arrangement of parts, hereinafter fully described, illustrated in the accompanying drawings, and pointed out in the claims hereto appended.

30 In the drawings, Figure 1 is a vertical sectional view of a washing-machine constructed in accordance with this invention. Fig. 2 is a plan view. Fig. 3 is a horizontal sectional view on line 3-3 of Fig. 1.

35 Like numerals of reference designate corresponding parts in all the figures of the drawings.

1 designates a vertical cylindrical receptacle designed to be constructed of sheet metal or other suitable material and provided with 40 a top 2 and a bottom 3 and supported and reinforced by top, bottom, and intermediate hoops. The receptacle is supported above the floor by suitable legs 4 to enable a bucket or other vessel to be placed beneath it, and 45 it has a spigot 5 to enable its liquid contents to be readily discharged into such vessel. The top 2, which is located below the upper edges of the sides of the receptacle 1, is provided with a central opening and is adapted 50 to receive a lid 6, having a depending flange 7 and seated upon a ring 8, of cast metal or other suitable material, secured to the lower

face of the top 2 and adapted to stiffen the same. The ring is provided with an annular recess at its upper face to receive the lid, and 55 the latter is preferably provided with a rubber gasket or ring 8^a to provide a tight joint. The projecting upper edges of the sides of the receptacle 1 are adapted to receive a wringer, so that the water expelled from the 60 clothes by the operation of wringing will run back into the receptacle. The receptacle may be provided with any suitable handles to enable it to be conveniently carried.

Mounted upon one side of the receptacle, 65 on the exterior of the same, is an air-pump 9, preferably secured to the central and lower hoops and composed of a vertical cylinder 10 and a piston 11, which has its rod 12 connected with an operating-lever 13 by a pitman 70 or link 14. The cylinder is provided at its bottom with a ball-valve 14^a, and it is provided at its top with openings to permit the air to pass into and out of the upper portion 75 of the cylinder as the piston reciprocates. The operating-lever, which is substantially L-shaped or of bell-crank form, is fulcrumed at its angle on a suitable bracket or support 15, and it has one arm pivoted to the upper end of the connecting link or pitman 14, and 80 its other end is provided with a suitable grip or handle whereby it is readily oscillated to reciprocate the piston of the air-pump.

85 The air-pump is connected at the center of its bottom directly beneath the valve-seat with an exhaust-pipe 16, and it is connected at its outer side with a discharge-pipe 17. The bracket or support 15, on which the operating-lever is fulcrumed, consists of a plate secured to the upper face of the top 2 and 90 provided with a pair of upwardly-extending arms, between which the lever is mounted. The suction-pipe or exhaust-pipe 16 preferably extends through the bottom of the receptacle 1, being composed of an inner vertical portion 16^a and an outer L-shaped portion extending horizontally beyond the receptacle at the bottom thereof and vertically to the center of the bottom of the cylinder. The upper end of the suction or exhaust pipe 16^a is arranged close to the top of the receptacle 1, and its greater portion is heated by the 95 contents of the latter. The exhaust-pipe is composed of suitable sections coupled to

gether, as illustrated in the accompanying drawings, and it will be readily apparent that it may communicate with the upper portion of the receptacle by being extended into the same at any portion thereof. The discharge-pipe, which extends from one side of the cylinder, as clearly illustrated in Fig. 1 of the accompanying drawings, is composed of inner and outer vertical portions and a horizontal connecting portion suitably coupled to the inner and outer portions. The inner portion is provided with a nipple or sleeve 18, engaging a collar 19 and forming a valve-seat at its upper end to receive a ball-valve 20. The ball-valve 20 is arranged within a perforated cage or cap 21, of cylindrical form, internally threaded at the bottom and screwing on the projecting portion of the sleeve or nipple. The operation of washing is effected by first soaking the clothes or other fabrics in cold water, which is drawn off through the spigot after the fabrics are thoroughly soaked. The receptacle is then supplied with hot water until it is about two-thirds full, and the pump is then operated. On the upstroke of the piston a suction is created in the exhaust or suction pipe and hot air and steam are drawn into the cylinder. The downstroke of the piston closes the valve 14 and forces the hot air and steam through the discharge-spout into the receptacle 1 at the bottom thereof. This produces a continuous circulation of hot air and steam, which results in agitating the clothes and forcing air and steam through them. The clothes are thus rapidly and thoroughly washed without wearing, tearing, or otherwise injuring them, and the washing-machine is especially adapted for operating on laces and analogous articles which cannot be washed in machines which rub or pound the fabrics. After being operated on in this manner the clothes are passed through the wringer (not shown) and the hot water is drawn off through the spigot 5. The clothes are again placed into the receptacle and subjected to cold water and to the action of the air-pump, by which they are thoroughly rinsed, so that after they are again passed through the wringer the operation of washing is completed.

The receptacle when the washing-machine is designed for laundry use may be connected with a boiler for supplying hot water, and pipe connections may be provided for

supplying cold water, and either a single or a double action air-pump may be employed, together with an engine for operating it.

It will be seen that the washing-machine is simple and comparatively inexpensive in construction, that it is capable of rapidly and thoroughly washing clothes with a minimum amount of labor and without injuring the fabrics, and that it is especially designed for operating on laces and analogous articles. It will also be apparent that the air-pump, which forces steam and hot air through the clothes, will also enable the clothes to be effectively rinsed.

What is claimed is—

1. A washing-machine comprising a receptacle provided with a lid or cover, an air-pump mounted on the exterior of the receptacle, an exhaust-pipe extending from the air-pump to the upper portion of the receptacle, and a discharge-pipe extending from the air-pump to the bottom of the receptacle, substantially as described.

2. A washing-machine comprising a receptacle provided with a lid or cover, an air-pump mounted on the exterior of the receptacle, an exhaust-pipe extending from the air-pump to the upper portion of the receptacle, a discharge-pipe extending from the air-pump to the bottom of the receptacle, an L-shaped operating-lever fulcrumed at its angle on the receptacle at the top thereof, and a pitman connecting the lever with the piston-rod of the air-pump, substantially as described.

3. A washing-machine comprising a receptacle, a vertical cylinder mounted on the exterior of the receptacle and provided at its bottom with a valve, a piston operating in the cylinder and having a vertical piston-rod, an exhaust or suction pipe extending from the bottom of the cylinder through the bottom of the receptacle to a point near the top thereof, a discharge-pipe extending from the cylinder to the bottom of the receptacle and provided with a valve, and operating mechanism connected with the piston-rod, substantially as described.

In testimony that I claim the foregoing as my own I have hereto affixed my signature in the presence of two witnesses.

WILLIAM J. GEORGE.
